UNITED STATES PATENT OFFICE.

JAMES MACPHAIL, OF BLUE ISLAND, ILLINOIS, ASSIGNOR TO THE PLANO MANUFACTURING COMPANY, OF CHICAGO, ILLINOIS.

REAPING-MACHINE.

SPECIFICATION forming part of Letters Patent No. 609,891, dated August 30, 1898.

Application filed January 22, 1897. Serial No. 620,170. (No model.)

To all whom it may concern:

Be it known that I, JAMES MACPHAIL, a citizen of the United States, residing at Blue Island, in the county of Cook and State of Illinois, have invented a certain new and useful Improvement in Reaping-Machines, which is fully set forth in the following specification, reference being had to the accompanying drawings, in which—

10 Figure 1 is a plan view of a reaping-machine constructed according to my invention. Fig. 2 is a side elevation thereof in the direction of the arrow of Fig. 1 with the driving-wheel omitted, showing the platform tilted 15 up. Fig. 3 is a similar elevation showing the platform tilted down. Fig. 4 is a rear elevation of the machine. Figs. 5 and 6 are detail views of the attachment of the tilting-lever to the tilting-rod. Fig. 7 is a detail elevation of the seat-casting. Fig. 8 is a plan view of the same.

My invention relates to reaping-machines, and particularly to mechanism therein adapted to tilt the platform and raise or lower the 25 sickle-bar and to the seat-mounting and connections.

In the drawings I have omitted certain parts of the complete machine which have no connection with my improvement, and many 30 of the parts shown are of ordinary construction and will be but briefly described.

Referring to the drawings by letter, A represents the platform, A' the sickle-bar, B the grain-wheel, and C the gear-frame, of a reaping-machine. The driving-wheel D is mounted upon an axle D', forming part of the wheel-frame E. To the said wheel-frame is secured a yoke E', in which is mounted the roller E². The gear-frame C is swung from 40 the roller E² by the U-bolts e passing over the same. The roller E² is disposed nearly in line with the axle of the grain-wheel B, and the forward edge of the platform is thus free to tilt up and down from the axis so 45 formed.

Upon the axle D', outside of the driving-wheel, I mount a casting F, comprising a sleeve F', adapted to surround and be secured to the said axle by the pin f, a forwardly-projecting arm F², and a short rearwardly-extending bracket F³. In the end of the arm

F² is formed a slot f', adapted to receive a stud or pivot f², upon which is pivotally mounted the foot-lever f⁴. The said lever has appropriate connections with the rake disposed in 55 the usual manner and only part of which are shown in Fig. 1. The seat F⁵ is mounted upon the post F⁶, to the lower end of which is secured the footboard F⁷. The post F⁶ is rigidly secured to a short horizontal bar F⁸, 60 the inner end of which fits within a box f³, formed in the bracket F³ of the casting F. The bar F⁸ is secured in the said box by the pin f⁴, which in turn is held by the cotter-pin f⁵. 65

Hitherto in this class of machines the seat and its connections have been so secured to the axle and the foot-lever so mounted upon the footboard, such as F⁷, that it has been impracticable to remove the seat when desired to drive the machine through a narrow gate. This has proved a great practical inconvenience, but is entirely obviated by the above construction, with which the seat may be readily removed by withdrawing the cotter-pin f⁵ and pin f⁴ and as quickly replaced again. The foot-lever being mounted upon the casting F in no wise interferes with this removal. 70 75

To the gear-frame C the rear end of a tongue 80 or pole G is pivoted, as at g. A diagonal brace-rod G' is also preferably employed pivoted at g' to the pole and at g² to the platform.

Referring more specifically to the tilting 85 mechanism, H is a casting comprising a short arm H', pivotally mounted, as at h, upon the axle D', a socket H², and a rack-segment H³. The suspending-bar H⁴ is pivoted, as at h', to a bracket H⁵, mounted upon and forming a 90 part of the gear-frame C. The other end of the suspending-rod is adjustably secured, through one of the perforations h², to the lower end of the rack-segment H³. The rear end of the carrying-bar I is rigidly mounted 95 in the socket H², above described. Its forward end is bent, as at I', and is adapted to slide in a guide-box I², mounted upon one side of the pole G.

A tilting lever J is pivotally mounted upon 100 the carrying-bar I, as at j. At its rearward end it is provided with a handle J', the dog

j', and hand-latch *j*², whereby the lever can be moved along and secured upon the rack-segment *H*³. The forward end of the lever *J* in front of its point of pivotal connection with the carrying-bar is provided with a short upwardly-extending arm *J*², to the upper end of which is secured one end of a coiled contraction-spring *J*³. The other end of the said spring is secured by an eyebolt and nut to a bracket *J*⁴, mounted upon the carrying-bar. Any other means equivalent to the bolt and nut *j*³, permitting the adjustment of the tension of the spring, may be employed.

To the tilting lever *J*, between its pivotal mounting upon the carrying-bar and the handle *J'*, is rigidly secured a small bracket *K*, in the lower part of which there is formed the bearing for a swivel-pin *K*'. The said pin is provided with a head *K*², in which is formed a screw-threaded aperture adapted to receive a screw-threaded rod *K*³. The upper end of the rod *K*³ is provided with a crank-handle *K*⁴. The lower end is rotatably mounted upon the platform, as at *K*⁵.

The operation of these parts will be readily understood in connection with the drawings. In Fig. 2 the machine is shown in its normal position, with the sickle-bar raised. When it is desired to lower the sickle-bar, the tilting lever *J* is moved down the rack-segment *H*³. The rod *K*³ is thus depressed in respect of the carrying-bar *I*, the forward end of which slides forward in the guide-box *I*². The front edge of the platform and the sickle-bar are thus lowered to any desired extent within the range of adjustment of the rack-segment. When it is desired to raise the sickle-bar, the tilting lever *J* is moved upward along the rack-segment and the front end of the platform is raised by the rod *K*³. During this operation the spring *J*³ materially assists the operator, aiding him in overcoming what otherwise is a very considerable weight, and the said spring may be so adjusted in tension as

to permit of the tilting of the machine with a minimum of exertion. By means of the adjustable suspension-bar *H*⁴ and the screw-threaded rod *K*³ it will be seen that the range of tilting of the platform can be adjusted either higher or lower.

Having thus described my invention, what I claim, and desire to secure by Letters Patent, is—

1. In a reaping-machine, the gear-frame *C* pivotally mounted in relation to the driving-wheel, the pole *G* pivotally attached to the gear-frame, the carrying-bar *I* pivotally mounted in relation to the driving-wheel and having its forward end slidably mounted on the pole *G* and the rear end formed in a segmental rack and adjustably connected to the gear-frame *C*, the substantially L-shaped lever *J* pivotally mounted on the bar *I* and having the spring-latch co-operating with the segmental rack, the screw-threaded rod *K*³ having bearings in the frame *C* and in the pivotal nut *K*² carried by the bar *I*, and the spring *J*³ connected to the bar *I* and to the upturned end of the lever *J*, substantially as and for the purposes described.

2. In a reaping-machine, the axle *D*'; the casting *F* mounted upon the axle; the foot-lever *F*⁴ mounted upon the casting; and the seat *F*⁵ and its connections detachably mounted in the said casting.

3. In a reaping-machine, the axle *D*'; the casting *F*, comprising the forwardly-extending arm *F*² and the bracket *F*³, provided with a box *f*³; the foot-lever *F*⁴ mounted in the said arm *F*²; the seat *F*⁵; the seat-post *F*⁶; and the horizontal bar *F*⁸ secured at one end to the seat-post and detachably secured at its opposite end in the box *f*³, substantially as described.

JAMES MACPHAIL.
